UNITED STATES PATENT OFFICE

WALTER E. SMITH, OF WARWICK DOWNS, RHODE ISLAND, ASSIGNOR TO C. G. KING & CO., INC., OF PROVIDENCE, RHODE ISLAND, A CORPORATION OF RHODE ISLAND

DESIGN FOR A SHOE ORNAMENT

Application filed July 24, 1929. Serial No. 32,185. Term of patent 3½ years.

To all whom it may concern:

Be it known that WALTER E. SMITH, a citizen of the United States, residing at Warwick Downs, in the county of Kent and State of Rhode Island, has invented a certain new, original, and ornamental Design for a Shoe Ornament, of which the following is a specification, reference being had to the accompanying drawings, forming a part thereof.

Fig. 1 is a front elevation of a shoe ornament embodying my new design.

Fig. 2 is an edge view thereof.

I claim:

The ornamental design for a shoe ornament substantially as shown.

In testimony whereof I affix my signature.

WALTER E. SMITH.
